4'-ALKYL SUBSTITUTED-3,3-SPIRO-7-SULFAMYL-THIAZIDE PRODUCTS

James M. Sprague, Gwynedd Valley, and Edward J. Cragoe, Jr., Montgomery County, Pa., assignors to Merck & Co., Inc., Rahway, N.J., a corporation of New Jersey

No Drawing. Filed May 8, 1961, Ser. No. 108,298

2 Claims. (Cl. 260—243)

This invention is concerned with novel 3,3-spiro-substituted - 3,4 - dihydro - 1,2,4 - benzothiadiazine - 1,1 - dioxides wherein the spiro substituent is a 6-membered alicyclic ring having at least one aliphatic substituent attached to the 4'-carbon of the spiro structure. The aliphatic substituent(s) advantageously is lower aliphatic having a total of no more than 6 carbon atoms and is either straight chain, branched chain or alicyclic. The 4'-aliphatic substituent(s) advantageously is selected either from the straight or branched chain aliphatic radicals derived from a hydrocarbon such as methyl, ethyl, propyl, isopropyl, butyl, isobutyl, sec.-butyl, tert.-butyl, pentyl, isopentyl, 1,1-dimethylpropyl, hexyl or any of the various branched chain, 6-carbon aliphatic radicals; or is selected from the alicyclic radicals preferably an alicyclic radical derived from a hydrocarbon, such as cyclopropyl, cyclobutyl, cyclopentyl, and cyclohexyl, the alicyclic structures being either unsubstituted or alkyl substituted but preferably having no more than a total of 6 carbon atoms in the 4'-substituent grouping.

The novel compounds of this invention also contain a sulfamyl substituent attached to the benzenoid moiety of the benzothiadiazine structure and preferably at least one additional substituent selected from halogen or halogen-like radicals, such as chlorine, bromine, fluorine, iodine, trifluoromethyl, trichloromethyl, dichloromethyl and the like; lower alkyl such as methyl, ethyl, propyl and the like or similar alkyl groups having a substituent, such as a halogen, attached to one or more of the carbons in the alkyl group; lower alkoxy such as methoxy, ethoxy, propoxy and the like; nitro or amino.

The preferred compounds are those wherein the spiro structure is 4-mono-substituted, the sulfamyl substituent is attached to the 7-position of the benzothiadiazine structure and the other substituents are attached preferably to either or both of the 5- and/or 6-positions of the benzothiadiazine nucleus.

While it is known that 7-sulfamyl-3,4-dihydro-1,2,4-benzothiadiazine-1,1-dioxide compounds (hydrochlorothiazide and related compounds) possess marked saluretic properties, it was surprisingly discovered that many 4'-aliphatic-3,3-spiro substituted-3,4-dihydro-1,2,4-benzothiadiazine-1,1-dioxide compounds are markedly more potent saluretic agents than hydrochlorothiazide and some of them possess from 5 to 10 times the potency of their non-spiro analogs. The novel compounds of this invention can be administered in dosage forms known to be suitable for the administration of the other benzothiadiazine saluretic agents either alone in the form of pills, capsules, tablets and the like or admixed with antihypertensive or other therapeutically effective compounds in a single dosage form. However, while it is generally necessary to administer 50 mg. of hydrochlorothiazide to effect an enhanced excretion of sodium and chloride ions, a similar enhancement of the sodium and chloride ion excretion can be effected by some of the novel compounds of this invention by oral administration of 5 or less milligrams of active ingredient. This dosage is far below the toxic dose as measured by acute toxicity studies in mice. For example 4'-methyl-6-chloro-7-sulfamylspiro-[1,2,4-benzothiadiazine-3(4H),1'-cyclohexane]-1,1-dioxide gives an oral

LD₅₀ in mice of 2,750 mg./kg., and an intravenous LD₅₀ of 548 mg./kg., and the intravenous LD₅₀ in mice of 4'-methyl - 6 - trifluoromethyl - 7 - sulfamylspiro - [1,2,4-benzothiadiazine - 3(4H),1' - cyclohexane] - 1,1 - dioxide is 512 mg./kg. As the novel compounds of this invention are substantially non-toxic, the therapeutic ratio is very great and the possibility of producing any undesirable side effects is considerably less than with the use of other benzothiadiazine type saluretic agents which also are known to be safe drugs for use in this type therapy.

The novel compounds of this invention can be prepared by several methods. One method which has been found very useful in preparing the novel compounds involves reacting the appropriate aminobenzenedisulfonamide and 4-substituted cyclohexanones with moderate heating. Where feasible, excess ketone can be employed for its solvent properties, although other solvents can be used instead. Some solvents which are found to be suitable include dimethylformamide, dioxane, diethylene glycol dimethyl ether, ethylene glycol dimethyl ether, and the like.

If it is desired to carry the reaction to completion more quickly, it can be catalyzed with potassium fluoride in dimethylformamide or with an acid such as sulfuric acid, methanesulfonic acid, benzenesulfonic acid, p-toluenesulfonic acid, or other aliphatic or aromatic sulfonic acids in other media.

Another very satisfactory method involves reacting the appropriate aminobenzenedisulfonamide and ketal. The ketal can be cyclic in structure or acyclic or in the form of its enol ether which is readily generated from the ketal under acid conditions. The reaction preferably is carried out with moderate heating in the presence of a solvent and a few drops of acid which catalyzes the reaction. Butanol was found to be an entirely satisfactory solvent, though other alcohols as 1-pentanol, propanol and the like or an alcohol admixed with other solvents as dioxane, diethylene glycol dimethyl ether, ethylene glycol dimethyl ether and the like can be used.

It will be apparent from the above discussion that the novel compounds of this invention can be prepared by reacting the appropriate aminobenzenedisulfonamide with a 4-substituted-cyclohexanone and that said ketone can be replaced by a reactive, functional derivative of the same, such as a ketal or an enol ether, or a ketimine or by a substance which under the reaction conditions in question is converted to the ketone, such as the hydrosulfite or cyano-hydrin of the ketone, and that the reaction can be effected with or without an added solvent and with or without a catalyst, but preferably with heating.

The preparation of representative compounds of this invention is described in more detail in the following examples wherein all melting points reported are decomposition points which are corrected except where otherwise stated and wherein the petroleum ether employed is Merck & Co. Inc.'s Benzin, B.P. 30-60° C. Some of the novel compounds of this invention undergo appreciable hydrolysis in hot aqueous media. Recrystallizations involving a water component, therefore, were done at room temperature or below. These substances usually are dissolved in an organic solvent, cooled, stirred and water slowly added. Under these conditions the product often separates in crystalline form with high purity. When non-aqueous solvents are employed, recrystallizations are carried out in the conventional manner using hot solvents.

EXAMPLE 1

4' - sec. - butyl - 6 - trifluoromethyl - 7 - sulfamylspiro-[1,2,4 - benzothiadiazine - 3(4H),1' - cyclohexane]-1,1-dioxide

70 4 - amino - 6 - trifluoromethyl - 1,3 - benzenedisulfonamide (6.4 g., 0.02 mole) and 4-sec.-butylcyclohexanone

(6.1 g., 0.04 mole) are dissolved in dimethylformamide (25 ml.) and heated on a steam bath for 48 hours. The reaction mixture is cooled, treated with methanol (100 ml.) and then water (300 ml.) gradually is added with stirring. The aqueous layer is decanted and the residual viscous oily product is triturated with petroleum ether (100 ml.). The resulting solid is removed by filtration and dried. This material is dissolved in methanol (25 ml.) and treated with a few milliliters of water, and the small amount of oil that forms is removed by filtration. The filtrate is slowly treated with water (75 ml.) whereby a 71% yield of 4'-sec.-butyl-6-trifluoromethyl-7-sulfamyl-spiro - [1,2,4 - benzothiadiazine - 3(4H),1' - cyclohexane]-1,1-dioxide is obtained as a pure crystalline product melting at 231.5-232.5° C.

Analysis.—Calculated for $C_{17}H_{24}F_3N_3O_4S_2$: C, 44.82; H, 5.31; N, 9.23. Found: C, 45.04; H, 5.28; N, 9.16.

EXAMPLE 2

4' - cyclohexyl - 6 - chloro - 7 - sulfamylspiro - [1,2,4 - benzothiadiazine-3(4H),1'-cyclohexane]-1,1-dioxide

4-amino-6-chloro-1,3-benzenedisulfonamide (17.1 g., 0.02 mole), 4-cyclohexylcyclohexanone (14.42 g., 0.08 mole) are dissolved in dimethylformamide (90 ml.). Anhydrous potassium fluoride (7.0 g., 0.12 mole) is added and the mixture heated on the steam bath under anhydrous conditions for 20 hours. The solution is poured into 500 ml. of cold water. The liquid is decanted and the residue is triturated in several portions of petroleum ether. The solid that separates is removed by filtration, dried and recrystallized by dissolving in ethanol and slowly adding water giving a 24% yield of 4'-cyclohexyl-6 - chloro - 7 - sulfamylspiro[1,2,4 - benzothiadiazine-3(4H),1'-cyclohexane]-1,1-dioxide, melting point 252.5-253.5° C.

Analysis.—Calculated for $C_{18}H_{26}ClN_3O_4S_2$: C, 48.25; H, 5.85; N, 9.38. Found: C, 48.14; H, 5.64; N, 9.26.

EXAMPLE 3

4' - cyclohexyl - 6 - trifluoromethyl - 7 - sulfamylspiro - [1,2,4 - benzothiadiazine - 3(4H),1' - cyclohexane]-1,1-dioxide

Step A.—4-cyclohexylcyclohexanone (1 mole), ethylene glycol (1.05 mole), benzene (200 ml.) and p-toluenesulfonic acid (200 mg.) are placed in a flask fitted with a modified Dean-Stark constant water separator attached to a reflux condenser. The reaction mixture is vigorously refluxed until aqueous distillate no longer distilled and separated. The 8-cyclohexyl-1,4-dioxaspiro[4.5]decane, B.P. 117° C. at 0.4 mm. pressure, M.P. 42.5-43.5° C., is isolated by careful fractionation of the reaction mixture.

Analysis.—Calculated for $C_{14}H_{24}O_2$: C, 74.95; H, 10.75. Found: C, 75.16; H, 10.68.

Step B.—4 - amino - 6 - trifluoromethyl - 1,3 - benzenedisulfonamide (6.4 g., 0.02 mole) and 8-cyclohexyl-1,4-dioxaspiro[4,5]decane (8.97 g., 0.04 mole) are placed in a 200 ml., 3-necked flask fitted with a thermometer, mechanical stirrer and reflux condenser capped with a drying tube. Dry n-butyl alcohol (70 ml.) and concentrated sulfuric acid (3 drops) are added and the stirrer started. The mixture is heated at 80° C. for 3 hours and then at reflux for 4 hours. The reaction mixture is concentrated at reduced pressure to a volume of 15-20 ml. The addition of petroleum ether gives a solid which is removed by filtration and dried. This crude product (10.1 g.) is dissolved in ethyl acetate (about 15 ml.) and slowly treated with petroleum ether. The crystalline solid that separates (6.5 g.) is dissolved in methanol (about 25 ml.), treated with decolorizing charcoal and filtered. The filtrate is stirred and slowly treated with water to incipient precipitation. Upon standing, 2 g. (21%) of nearly pure 4'-cyclohexyl - 6 - trifluoromethyl - 7 - sulfamylspiro[1,2,4 - benzothiadiazine - 3(4H),1' - cyclohexane]-1,1 - dioxide

separates, M.P. 245-246.5° C. A final recrystallization is carried out by dissolving the compound in acetone (20 ml.) and adding a small volume of petroleum ether to precipitate a small amount of dark material which is removed by filtration. The filtrate is slowly treated with petroleum ether (220 ml. total) whereby the pure product separates as a white solid, M.P. 256-257° C. The yield of pure compound is 1.50 g. (16%).

Analysis.—Calculated for $C_{19}H_{26}ClN_3O_4S_2$: C, 47.38; H, 5.44; N, 8.73. Found: C, 47.22; H, 5.67; N, 8.62.

EXAMPLE 4

4'-methyl-6-chloro-7-sulfamylspiro-[1,2,4-benzothiadiazine-3(4H),1'-cyclohexane]-1-dioxide

15 4-amino-6-chloro-1,3-benzenedisulfonamide (5.7 g., 0.02 mole), 4-methylcyclohexanone (60 ml.) and p-toluenesulfonic acid (50 mg.) are refluxed under anhydrous conditions for 15 minutes. After cooling, the reaction mixture is poured into petroleum ether (450 ml.), the upper layer is decanted and the residual oil triturated with more petroleum ether. The solvent is decanted and the residue treated with warm methanol (100 ml.). A solid (2.9 g.) forms which is removed by filtration and the filtrate treated with cold water to give 20 another 4 g. of product. The combined yield of 4'-methyl-6-chloro - 7 - sulfamylspiro - [1,2,4 - benzothiadiazine-3(4H),1'-cyclohexane]-1,1-dioxide is 6.9 g. (91%). This material is dissolved in warm 2-methoxyethanol (25 ml.), cooled, stirred and very slowly treated with cold water 25 (240 ml.) to give a 70% yield of 4'-methyl-6-chloro-7-sulfamylspiro-[1,2,4-benzothiadiazine-3(4H),1'-cyclohexane]-1,1-dioxide in the form of large white crystals, M.P. 272-273° C.

Analysis.—Calculated for $C_{13}H_{18}ClN_3O_4S_2$: C, 41.10; H, 4.78; N, 11.06. Found: C, 40.99; H, 4.93; N, 10.96.

EXAMPLE 5

4'-methyl-6-chloro-7-sulfamylspiro-[1,2,4-benzothiadiazine-3(4H),1'-cyclohexane]-1,1-dioxide

40 4-amino-6-chloro - 1,3 - benzenedisulfonamide (0.02 mole), 4-methylcyclohexanone (0.08 mole) and p-toluenesulfonic acid (100 mg.) are suspended in p-dioxane (50 ml.). The mixture is refluxed and mechanically stirred for 30 hours and the solution that results is cooled and slowly 45 treated with cold water until crystallization of the product is complete. The solid material is collected on the filter and dried to give 4'-methyl-6-chloro-7-sulfamylspiro-[1,2,4-benzothiadiazine-3(4H),1'-cyclohexane]-1,1-dioxide.

EXAMPLE 6

4'-methyl-6-chloro-7-sulfamylspiro-[1,2,4-benzothiadiazine-3(4H),1'-cyclohexane]-1,1-dioxide

50 By replacing the aminobenzenedisulfonamide and the 55 ketone reactants employed in Example 1 by equimolecular quantities of 4-amino-6-chloro-1,3-benzenedisulfonamide and 4-methylcyclohexanone respectively, and following substantially the same procedure described in Example 1, there is obtained a 59% yield of 4'-methyl-6-chloro-6 7-sulfamylspiro-[1,2,4 - benzothiadiazine-3(4H),1'-cyclohexane]-1,1-dioxide which, after recrystallization from 2-methoxyethanol and water, has a melting point of 272-273° C.

Analysis.—Calculated for $C_{13}H_{18}ClN_3O_4S_2$: C, 41.10; H, 4.78; N, 11.06. Found: C, 40.77; H, 4.92; N, 11.24.

EXAMPLE 7

4'-methyl-6-trifluoromethyl-7-sulfamylspiro-[1,2,4-benzothiadiazine-3(4H),1'-cyclohexane]-1,1-dioxide

70 By replacing the ketone employed in Example 1 by an 75 equimolecular quantity of 4-methylcyclohexanone and following substantially the same procedure described in Example 1 there is obtained a 61% yield of 4'-methyl-6-trifluoromethyl-7-sulfamylspiro - [1,2,4-benzothiadiazine-

5

3(4H),1'-cyclohexane]-1,1-dioxide which, after recrystallization from methanol and water, melts at 247-249° C.

Analysis.—Calculated for $C_{14}H_{18}F_3N_3O_4S_2$: C, 40.67; H, 4.39; N, 10.16. Found: C, 40.78; H, 4.49; N, 10.09.

EXAMPLE 8

5

4'-methyl-5,6-dichloro-7-sulfamylspiro-[1,2,4-benzothiadiazine-3(4H),1'-cyclohexane]-1,1-dioxide

4-amino-5,6-dichloro-1,3-benzenedisulfonamide (12.8 g., 0.04 mole) and 4-methylcyclohexanone (13.5 g., 0.12 mole) are dissolved in dimethylformamide (60 ml.) and heated on a steam bath for 22 hours. The solution is cooled, treated with 100 ml. of methanol then with water to incipient crystallization. After standing, there is obtained a 79% yield of 4'-methyl-5,6-dichloro-7-sulfamylspiro-[1,2,4-benzothiadiazine-3(4H),1'-cyclohexane]-1,1-dioxide which, after recrystallization from acetone and petroleum ether, melts at 273-274° C.

Analysis.—Calculated for $C_{18}H_{17}ClN_3O_4S_2$: C, 37.68; H, 4.19; N, 10.14. Found: C, 38.17; H, 4.06; N, 10.09.

EXAMPLE 9

20

4'-methyl-6-nitro-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-nitro-1,3-benzenedisulfonamide and 4-methylcyclohexanone respectively, and following substantially the same procedure described in Example 1, there is obtained a 35% yield of 4'-methyl-6-nitro-7-sulfamylspiro-[1,2,4-benzothiadiazine-3(4H),1'-cyclohexane]-1,1-dioxide which, after recrystallization from acetone and water melts at 255-256° C.

Analysis.—Calculated for $C_{18}H_{18}N_4O_6S_2$: C, 40.61; H, 4.72; N, 14.57. Found: C, 40.27; H, 4.64; N, 14.32.

The corresponding 6-amino compound can be prepared either by the process described in Example 9 using equimolecular quantities of 4,6-diamino-1,3-benzenedisulfonamide and the ketone reactants, or by reducing the 6-nitro compound obtained by the process of Example 9. Reduction can be effected by dissolving the 6-nitro compound in alcohol and shaking in an atmosphere of hydrogen in the presence of platinum until hydrogen absorption ceases. The catalyst can be removed by filtration and the solvents removed by drying in vacuo to give 4'-methyl-6-amino-7-sulfamylspiro-[1,2,4-benzothiadiazine-3(4H),1'-cyclohexane]-1,1-dioxide.

EXAMPLE 10

40

4',6-dimethyl-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-methyl-1,3-benzenedisulfonamide and 4-methylcyclohexanone respectively, and following substantially the same procedure described in Example 1, there is obtained a 43% yield of 4',6-dimethyl-7-sulfamylspiro-[1,2,4-benzothiadiazine-3(4H),1'-cyclohexane]-1,1-dioxide which, after recrystallization from acetone and petroleum ether, melts at 250.5° C.

Analysis.—Calculated for $C_{14}H_{21}N_3O_4S_2$: C, 45.20; H, 5.54; N, 12.16. Found: C, 45.19; H, 5.40; N, 11.92.

EXAMPLE 11

50

4'-ethyl-6-chloro-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-chloro-1,3-benzenedisulfonamide and 4-ethylcyclohexanone respectively, heating for 20 hours on a steam bath, and following substantially the same procedure described in Example 1, there is obtained a 56% yield of 4'-ethyl-6-chloro-7-sulfamylspiro-[1,2,4-benzothiadiazine-3(4H),1'-cyclohexane]-1,1-dioxide,

6

which, after crystallization from acetone and petroleum ether melts at 248-249° C.

Analysis.—Calculated for $C_{14}H_{20}ClN_3O_4S_2$: C, 42.68; H, 5.12; N, 10.67. Found: C, 43.16; H, 5.20; N, 10.58.

EXAMPLE 12

5

4'-ethyl-6-trifluoromethyl-7-sulfamylspiro-[1,2,4-benzothiadiazine-3(4H),1'-cyclohexane]-1,1-dioxide

By replacing the ketone employed in Example 1 by an equimolecular quantity of 4-ethylcyclohexanone, heating for 24 hours on a steam bath and following substantially the same procedure described in Example 1, there is obtained a 29% yield of 4'-ethyl-6-trifluoromethyl-7-sulfamylspiro-[1,2,4-benzothiadiazine-3(4H),1'-cyclohexane]-1,1-dioxide which, after several recrystallizations from methanol and water, melts at 261-262° C.

Analysis.—Calculated for $C_{15}H_{20}F_3N_3O_4S_2$: C, 42.14; H, 4.72; N, 9.83. Found: C, 42.45; H, 4.89; N, 9.76.

EXAMPLE 13

20

4'-propyl-6-chloro-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-chloro-1,3-benzenedisulfonamide and 4-propylcyclohexanone respectively, heating for 20 hours, and following substantially the same procedure described in Example 1, there is obtained a 36% yield of 4'-propyl-6-chloro-7-sulfamylspiro-[1,2,4-benzothiadiazine-3(4H),1'-cyclohexane]-1,1-dioxide which, after recrystallization from acetone and petroleum ether, melts at 245-246° C.

Analysis.—Calculated for $C_{15}H_{22}ClN_3O_4S_2$: C, 44.16; H, 5.44; N, 10.30. Found: C, 44.08; H, 5.33; N, 10.21.

EXAMPLE 14

30

4'-propyl-6-trifluoromethyl-7-sulfamylspiro-[1,2,4-benzothiadiazine-3(4H),1'-cyclohexane]-1,1-dioxide

By replacing the ketone employed in Example 1 by an equimolecular quantity of 4-propylcyclohexanone and following substantially the same procedure described in Example 1, there is obtained an 82% yield of 4'-propyl-6-trifluoromethyl-7-sulfamylspiro-[1,2,4-benzothiadiazine-3(4H),1'-cyclohexane]-1,1-dioxide which, after recrystallization from methanol and water, melts at 225-227° C.

Analysis.—Calculated for $C_{16}H_{22}F_3N_3O_4S_2$: C, 43.52; H, 5.02; N, 9.52. Found: C, 43.93; H, 5.34; N, 9.39.

EXAMPLE 15

50

4'-isopropyl-6-chloro-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-chloro-1,3-benzenedisulfonamide and 4-isopropylcyclohexanone respectively, heating for 72 hours on a steam bath and treating the solution with 70 ml. of acetic acid and sufficient water to cause incipient crystallization there is obtained a 53% yield of 4'-isopropyl-6-chloro-7-sulfamylspiro-[1,2,4-benzothiadiazine-3(4H),1'-cyclohexane]-1,1-dioxide which, after recrystallization from acetone and petroleum ether melts at 259-260° C.

Analysis.—Calculated for $C_{15}H_{22}ClN_3O_4S_2$: C, 44.16; H, 5.44; N, 10.30. Found: C, 44.56; H, 5.30; N, 10.19.

EXAMPLE 16

70

4'-butyl-6-chloro-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-chloro-1,3-benzenedisulfonamide and 4-butylcyclohexanone respectively, and following substantially the same procedure described in Example

75

1, there is obtained a 40% yield of 4'-butyl-6-chloro-7-sulfamylspiro - [1,2,4-benzothiadiazine-3(4H),1'-cyclohexane]-1,1-dioxide which, after recrystallization from acetone and petroleum ether, melts at 216.5-217.5° C.

Analysis.—Calculated for $C_{16}H_{24}ClN_3O_4S_2$: C, 45.54; H, 5.73; N, 9.96. Found: C, 45.26; H, 5.93; N, 9.87.

EXAMPLE 17

4'-sec.-butyl-6-chloro-7-sulfamylspiro-[1,2,4-benzothiadiazine-3(4H),1'-cyclohexane]-1,1-dioxide

By replacing the aminobenzenedisulfonamide employed in Example 1 by an equimolecular quantity of 4-amino-6-chloro-1,3-benzenedisulfonamide, heating for 21 hours, treating the solution with 100 ml. of acetic acid and sufficient water to cause incipient crystallization, there is obtained a 25% yield of 4'-sec.-butyl-6-chloro-7-sulfamylspiro-[1,2,4-benzothiadiazine-3(4H),1'-cyclohexane]-1,1-dioxide which, after recrystallization from acetone and petroleum ether, melts at 248-249° C.

Analysis.—Calculated for $C_{16}H_{24}ClN_3O_4S_2$: C, 45.54; H, 5.73; N, 9.96. Found: C, 45.83; H, 5.73; N, 9.89.

EXAMPLE 18

4'-tert.-butyl-6-chloro-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-chloro-1,3-benzenedisulfonamide and 4-tert.-butylcyclohexanone respectively, heating for 44 hours on a steam bath and treating the solution with 200 ml. of acetic acid, there is obtained a 30% yield of 4'-tert.-butyl-6-chloro-7-sulfamylspiro-[1,2,4-benzothiadiazine-3(4H),1'-cyclohexane]-1,1-dioxide which melts at 276-277° C.

Analysis.—Calculated for $C_{16}H_{24}ClN_3O_4S_2$: C, 45.54; H, 5.73; N, 9.96. Found: C, 45.48; H, 5.50; N, 9.80.

EXAMPLE 19

4'-tert.-butyl-6-trifluoromethyl-7-sulfamylspiro-[1,2,4-benzothiadiazine-3(4H),1'-cyclohexane]-1,1-dioxide

4-amino-6-trifluoromethyl - 1,3 - benzenedisulfonamide (6.4 g., 0.02 mole) and 4-tert.-butylcyclohexanone (9.2 g., 0.06 mole) are dissolved in dimethylformamide (30 ml.) and heated on a steam bath for 45 hours. The solution is reduced in volume to 15 ml. and dissolved in 100 ml. of ether. The ether solution is extracted with 10% aqueous sodium hydroxide (50 ml.). Upon neutralization of the basic solution with 6 N hydrochloric acid there is obtained a 69% yield of 4'-tert.-butyl-6-trifluoromethyl-7-sulfamylspiro - [1,2,4-benzothiadiazine-3(4H),1'-cyclohexane]-1,1-dioxide which, after recrystallization from acetone and petroleum ether, melts at 252.5-254° C.

Analysis.—Calculated for $C_{17}H_{24}F_3N_3O_4S_2$: C, 44.82; H, 5.31; N, 9.23. Found: C, 45.01; H, 5.56; N, 9.15.

EXAMPLE 20

4'-isopentyl-6-chloro-7-sulfamylspiro-[1,2,4-benzothiadiazine-3(4H),1'-cyclohexane]-1,1-dioxide

By replacing the aminobenzenedisulfonamide and the ketone reactants employed in Example 1 by equimolecular quantities of 4-amino-6-chloro-1,3-benzenedisulfonamide and 4-isopentylcyclohexanone respectively, heating for 18 hours on a steam bath and treating the solution with 80 ml. of acetic acid, then with 375 ml. of water there is obtained a 39% yield of 4'-isopentyl-6-chloro-7-sulfamylspiro-[1,2,4-benzothiadiazine-3(4H),1'-cyclohexane]-1,1-dioxide which, after recrystallization from ethanol and water, melts at 240-242° C.

Analysis.—Calculated for $C_{17}H_{26}ClN_3O_4S_2$: C, 46.83; H, 6.01; N, 9.64. Found: C, 46.69; H, 6.41; N, 9.54.

EXAMPLE 21

4'-(1,1-dimethylpropyl)-6-chloro-7-sulfamylspiro-[1,2,4-benzothiadiazine-3(4H),1'-cyclohexane]-1,1-dioxide

5 By replacing the aminobenzenedisulfonamide and the ketone reactants employed in Example 1 by equimolecular quantities of 4-amino-6-chloro-1,3-benzenedisulfonamide and 4-(1,1-dimethylpropyl)cyclohexanone respectively, heating for 24 hours on a steam bath, treating with 100 ml. of acetic acid, then water to incipient crystallization, there is obtained a 34% yield of 4'-(1,1-dimethylpropyl)-6-chloro-7-sulfamylspiro - [1,2,4-benzothiadiazine-3(4H),1'-cyclohexane]-1,1-dioxide which, after recrystallization from acetone and petroleum ether melts at 262-263° C.

10 *Analysis.*—Calculated for $C_{17}H_{28}ClN_3O_4S_2$: C, 46.83; H, 6.01; N, 9.64. Found: C, 46.66; H, 5.80; N, 9.55.

EXAMPLE 22

4'-cyclopentyl-6-chloro-7-sulfamylspiro-[1,2,4-benzothiadiazine-3(4H),1'-cyclohexane]-1,1-dioxide

20 By replacing the aminobenzenedisulfonamide and the ketone reactants employed in Example 1 by equimolecular quantities of 4-amino-6-chloro-1,3-benzenedisulfonamide and 4-cyclopentylcyclohexanone respectively, treating the solution with 90 ml. of acetic acid, then with water to incipient crystallization, there is obtained a 44% yield of 4'-cyclopentyl-6-chloro-7-sulfamylspiro-[1,2,4-benzothiadiazine-3(4H),1'-cyclohexane]-1,1-dioxide which, after recrystallization from acetone and petroleum ether, melts at 239-242° C.

25 *Analysis.*—Calculated for $C_{17}H_{24}ClN_3O_4S_2$: C, 47.04; H, 5.57; N, 9.68. Found: C, 47.60; H, 5.54; N, 9.54.

EXAMPLE 23

4'-methyl-6-pentafluoroethyl-7-sulfamylspiro-[1,2,4-benzothiadiazine-3(4H),1'-cyclohexane]-1,1-dioxide

(Step A) Preparation of *m*-(pentafluoroethyl)nitrobenzene.—(Pentafluoroethyl)benzene (74 g., 0.4 mole) is

40 stirred and cooled to 5° C. and treated dropwise with a mixture of nitric acid (d. 1.5, 22 g., 0.33 mole) and concentrated sulfuric acid (33 g., 0.32 mole). Temperature is maintained at 5-15° C. during the 1 hour addition time and then raised to 45° C. for 1 hour. The reaction mixture is cooled, poured into ice, and the oil that separates is extracted with ether, washed with water, dried over sodium sulfate and fractionally distilled to give 84 g. (87%) of *m*-(pentafluoroethyl)nitrobenzene boiling at 74-75° C. at 0.35 mm. pressure, n_D^{25} 1.4382.

45 *Analysis.*—Calculated for $C_8H_4F_5O_2N$: C, 39.84; H, 1.67; N, 5.81. Found: C, 40.21; H, 1.90; N, 5.69.

(Step B) Preparation of *m*-(pentafluoroethyl)aniline.—*m*-(Pentafluoroethyl)nitrobenzene (11.0 g., 0.457 mole) is dissolved in ethanol (450 ml.) and catalytically hydrogenated in the presence of Raney nickel at 30° C. and 2300 p.s.i. hydrogen pressure for 5 hours. The catalyst then is removed by filtration and the filtrate fractionally distilled using a 14 inch Vigreux column to give 87 g. (95%) of *m*-(pentafluoroethyl)aniline boiling at 80-82° C. at 14 mm. pressure, n_D^{25} 1.4478.

50 *Analysis.*—Calculated for $C_8H_6F_5N$: C, 45.50; H, 2.86; N, 6.63. Found: C, 45.88; H, 2.90; N, 6.44.

(Step C) Preparation of 4-amino-6-pentafluoroethyl-1,3-benzenedisulfonamide.—Under anhydrous conditions,

55 chlorosulfonic acid (177 g., 100 ml., 1.52 moles) is mechanically stirred and *m*-(pentafluoroethyl)aniline (20 g., 0.095 mole) is added at room temperature over a 20 minute period. Sodium chloride (90 g., 1.55 mole) is added portionwise over a period of 90 minutes. Considerable foaming occurred particularly during the early part of the addition. The reaction vessel is placed in an oil bath and the temperature raised to 150° C. over a period of 30 minutes and then held there for two hours. During the heating period, the contents of the reaction vessel solidified. The mixture is cooled, quenched with ice water (500

ml.) and extracted with ether (300 ml.). The ether extract is washed with water, dried over sodium sulfate, concentrated to a volume of 100 ml. and added to liquid ammonia (250 ml.). The solid that forms upon evaporation of the volatile material is triturated with hot benzene (two 100 ml. portions), dried and recrystallized twice from water to give 19.7 g. (56%) of 4-amino-6-pentafluoroethyl-1,3-benzenedisulfonamide, M.P. 242.5-243° C.

Analysis.—Calculated for $C_8H_8F_5N_3O_4S_2$: C, 26.02; H, 2.18; N, 11.38; S, 17.91. Found: C, 26.59; H, 2.29; N, 11.26; S, 17.50.

(Step D) *Preparation of 4'-methyl-6-pentafluoroethyl-7-sulfamylspiro-[1,2,4-benzothiadiazine-3(4H),1'-cyclohexane]-1,1-dioxide.*—By replacing the 4-amino-6-chloro-1,3-benzenedisulfonamide employed in Example 4 by an equimolecular quantity of 4-amino-6-pentafluoroethyl-1,3-benzenedisulfonamide, heating under reflux for 1½ hours, and following substantially the same procedure described in Example 4, there is obtained a 56% yield of 4'-methyl-6-pentafluoroethyl-7-sulfamylspiro-[1,2,4-benzothiadiazine-3(4H),1'-cyclohexane]-1,1-dioxide which, after recrystallization from acetic acid and water, melts at 222-223.5° C.

Analysis.—Calculated for $C_{15}H_{18}F_5N_3O_4S_2$: C, 38.87; H, 3.91; N, 9.07. Found: C, 39.05; H, 4.18; N, 8.90.

EXAMPLE 24

4',4'-dimethyl-6-chloro-7-sulfamylspiro-[1,2,4-benzothiadiazine-3(4H),1'-cyclohexane]-1,1-dioxide

By replacing the ketone employed in Example 2 by an equimolecular quantity of 4,4-dimethylcyclohexanone and following substantially the same procedure described in Example 2 there is obtained 4',4'-dimethyl-6-chloro-7-sulfamylspiro-[1,2,4-benzothiadiazine-3(4H),1'-cyclohexane]-1,1-dioxide.

EXAMPLE 25

4'-methyl-6-bromo-7-sulfamylspiro-[1,2,4-benzothiadiazine-3(4H),1'-cyclohexane]-1,1-dioxide

By replacing the aminobenzenedisulfonamide and the ketone reactants employed in Example 2 by equimolecular quantities of 4-amino-6-bromo-1,3-benzenedisulfonamide and 4-methylcyclohexanone respectively, and following substantially the same procedure described in Example 2, there is obtained 4'-methyl-6-bromo-7-sulfamylspiro-[1,2,4-benzothiadiazine-3(4H),1'-cyclohexane]-1,1-dioxide.

EXAMPLE 26

4'-methyl-6-methoxy-7-sulfamylspiro-[1,2,4-benzothiadiazine-3(4H),1'-cyclohexane]-1,1-dioxide

By replacing the aminobenzenedisulfonamide and the ketone reactants employed in Example 2 by equimolecular quantities of 4-amino-6-methoxy-1,3-benzenedisulfonamide and 4-methylcyclohexanone respectively, and following substantially the same procedure described in Example 2, there is obtained 4'-methyl-6-methoxy-7-sulfamylspiro-[1,2,4-benzothiadiazine-3(4H),1'-cyclohexane]-1,1-dioxide.

EXAMPLE 27

4'-methyl-6-fluoro-7-sulfamylspiro-[1,2,4-benzothiadiazine-3(4H),1'-cyclohexane]-1,1-dioxide

By replacing the aminobenzenedisulfonamide and the ketone reactants employed in Example 2 by equimolecular quantities of 4-amino-6-fluoro-1,3-benzenedisulfonamide and 4-methylcyclohexanone respectively, and following substantially the same procedure described in Example 2, there is obtained 4'-methyl-6-fluoro-7-sulfamylspiro-[1,2,4-benzothiadiazine-3(4H),1'-cyclohexane]-1,1-dioxide.

EXAMPLE 28

4'-methyl-6-sulfamyl-7-chlorospiro-[1,2,4-benzothiadiazine-3(4H),1'-cyclohexane]-1,1-dioxide

By replacing the aminobenzenedisulfonamide and the ketone reactants employed in Example 2 by equimolecular

quantities of 1-chloro-4-amino-3,6-benzenedisulfonamide and 4-methylcyclohexanone respectively, and following substantially the same procedure described in Example 2, there is obtained 4'-methyl-6-sulfamyl-7-chlorospiro-[1,2,4-benzothiadiazine-3(4H),1'-cyclohexane]-1,1-dioxide.

EXAMPLE 29

4'-methyl-7-sulfamylspiro-[1,2,4-benzothiadiazine-3(4H),1'-cyclohexane]-1,1-dioxide

By replacing the aminobenzenedisulfonamide employed in Example 1 by an equimolecular quantity of 4-amino-1,3-benzenedisulfonamide and following substantially the same procedure described in Example 1 there is obtained 4'-methyl-7-sulfamylspiro-[1,2,4-benzothiadiazine-3(4H),1'-cyclohexane]-1,1-dioxide, M.P. 247-249° C.

Analysis.—Calculated for $C_{13}H_{19}N_3O_4S_2$: C, 45.20; H, 5.54; N, 12.16. Found: C, 45.20; H, 5.57; N, 12.09.

The dosage of the novel compounds of this invention will vary over a wide range, and for this reason tablets, pills, capsules, powders and the like containing from about 5 mg. to about 200 mg. or more of active ingredient can be made available to the physician for the symptomatic adjustment of the dosage to the individual patient. As each of the compounds can be incorporated in a dosage form similar to those described in the following examples or in other dosage forms suitable for oral or parenteral administration which can be made by well known methods, only a few examples are included herein to illustrate the preparation of representative dosage forms.

EXAMPLE 30

Compressed tablet containing 4 mg. of active ingredient

	Per tablet, mg.
4'-methyl-6-chloro-7-sulfamylspiro-[1,2,4-benzothiadiazine-3(4H), 1'-cyclohexane]-1,1-dioxide	4
40 Lactose	96
30 Starch as 10% paste	2
	102
45 Add:	
45 Cornstarch	12
45 Magnesium stearate	1
	115

50 The 4'-methyl-6-chloro-7-sulfamylspiro-[1,2,4-benzothiadiazine-3(4H), 1'-cyclohexane]-1,1-dioxide and the lactose are thoroughly mixed and then reduced to fine particle size. The mixture then is granulated with the starch paste and passed through a No. 10 screen, dried overnight at 120° C. and then dry-granulated through a 55 No. 30 mesh. The cornstarch and magnesium stearate then are added and thoroughly incorporated in the mixture and the tablets compressed on an $\frac{5}{32}$ inch flat, bevelled scored punch. The tablets produced have a thickness of 2.80 mm. and a hardness of 5½ kg. when tested 60 by the Monsanto gun.

EXAMPLE 31

Dry filled capsules containing 5 mg. of active ingredient

	Per capsule, mg.
4' - methyl - 6 - trifluoromethyl - 7 - sulfamylspiro-[1,2,4-benzothiadiazine-3(4H), 1'-cyclohexane]-1,1-dioxide	1
70 Lactose	195

75 The 4'-methyl-6-trifluoromethyl-7-sulfamylspiro-[1,2,4-benzothiadiazine-3(4H), 1'-cyclohexane]-1,1-dioxide is reduced to a No. 60 powder. Lactose then is passed through a No. 60 bolting cloth onto the powder. The combined in-

ingredients are admixed for 10 minutes and then filled into No. 2 dry gelatin capsules.

As each of the compounds of this invention can be incorporated in a dosage form similar to those described above or in other dosage forms suitable for oral or parenteral administration which can be prepared by well-known methods, no additional examples are included herein to illustrate the preparation of representative dosage forms.

While the above examples describe the preparation of certain compounds which are illustrative of the novel compounds of this invention, and certain specific dosage forms suitable for administering the novel compounds of this invention can be prepared, it is to be understood that the invention is not to be limited to the specific compounds described in the examples or by the specific reaction conditions described for the preparation of the compounds or by the specific ingredients included in the pharmaceutical preparations, but is to be understood to embrace variations and modifications thereof which fall within the scope of the appended claims.

What is claimed is:

1. 4' - methyl - 6 - chloro - 7 - sulfamylspiro - [1,2,4-benzothiadiazine-3(4H), 1'-cyclohexane]-1,1-dioxide.
2. 4' - methyl - 6 - trifluoromethyl - 7 - sulfamylspiro - [1,2,4-benzothiadiazine-3(4H), 1'-cyclohexane]-1,1-dioxide.
